UNITED STATES PATENT OFFICE.

SIDNEY WILLIAMS, OF PROVIDENCE, RHODE ISLAND, ASSIGNOR TO WILLIAMS & ANDERSON, OF PROVIDENCE, RHODE ISLAND.

DESIGN FOR A CHARM OR SIMILAR ARTICLE.

SPECIFICATION forming part of Design No. 36,811, dated February 23, 1904.

Application filed December 29, 1903. Serial No. 187,072. Term of patent 7 years.

To all whom it may concern:

Be it known that I, SIDNEY WILLIAMS, a citizen of the United States, residing at Providence, in the county of Providence and State 5 of Rhode Island, have invented a new, original, and ornamental Design for a Charm or Similar Article, reference being had to the accompanying drawing.

The figure in the drawing represents a face 10 view of a charm embodying my design.

What I claim as new, and desire to secure by Letters Patent, is—

The ornamental design for a charm or similar article, as shown.

SIDNEY WILLIAMS.
